COMBINATION POT AND LOADING STAND

George S. Watrous, Jr., Derby, Conn.

Application June 4, 1935, Serial No. 24,829

16 Claims. (Cl. 263—47)

This invention relates to new and useful improvements in apparatus to be used in the heat treating of wire and has particular relation to a combination pot and loading stand for use when annealing wire.

An object of the invention is to provide a combination pot and loading stand so constructed that it is not necessary to invert the stand to unload it.

10 A further object is to provide an apparatus as stated and which does not require that the hood or cover do other than exclude gases and since it is only required to support its own weight may be made with a thin wall to reduce its bulk 15 and weight and to have it more readily transmit heat.

Another object is to provide an apparatus having the characteristics indicated and which will have long useful life.

20 Other objects and advantages will become apparent from a consideration of the following detailed description taken in connection with the accompanying drawing, wherein a satisfactory embodiment of the invention is shown. However, it will be understood that the invention is not limited to the details disclosed but includes all such variations and modifications as fall within the spirit of the invention and the 25 scope of the appended claims.

30 In the drawing:

Fig. 1 is an elevational view with parts broken away and showing an apparatus constructed according to the present invention;

35 Fig. 2 is a view, partly in elevation and partly in section showing the loading stand alone;

Fig. 3 is a top plan view of the complete apparatus; and

Fig. 4 is a sectional view taken substantially 40 along the line 4—4 of Fig. 2.

Referring in detail to the drawing the improved combination pot and loading stand as here shown includes a relatively heavy base 10 constructed to support the weight of the wire bundles with which the stand is to be loaded 45 and such base is provided centrally with a thickened or raised portion 11 providing a shoulder 12 the upper corner 13 of which is preferably rounded as shown in Fig. 2 so as to prevent wire catching thereon. Rigid with the portion 11 and extending upwardly therefrom is a tubular piece or collar 14 shown as fastened to the base in any suitable manner although it will later become apparent that this collar 14 might be integral 50 with the base.

55 Through its thickened portion the base is pro-

vided with a key shaped opening 15 and adjacent its outer edge it is provided in its upper surface with a groove 16 the purpose of which will later be described. In order to reduce the weight of the base its under side may be ribbed 5 as suggested at 17, the said ribs being arranged to engage a supporting surface to prevent crushing of the base under the load and also providing a structure wherein the base is of less weight due to the fact that it is not solid but 10 has spaces between its ribs.

A centering sleeve 18 (the outside diameter of which should be approximately the same as the diameter of the hole through a bundle of wire) is provided and this sleeve is mounted on the 15 base by telescoping the lower end of the sleeve over the collar 14, whereby the sleeve is properly located and is prevented from moving or tilting out of its proper position. When bundles of wire are to be loaded onto the stand the sleeve 18 20 is disposed over the collar 14 as described and a lifting rod 19 extends through the sleeve and through the opening 15 in the base and the bundles 28 are disposed about the sleeve as shown. At its upper end the lifting rod is provided with an eye 20 for the passage of a hook of a crane, and at its lower end the rod is provided with a lug 21 shaped to pass through the opening 15 in the base when properly aligned therewith. Also, on the rod 19 and within the 25 sleeve 18 are centering or locating discs 22 and 23.

Within and secured to the sleeve 18 above the upper locating disc 22 are a plurality of lugs 24 which lugs project into the sleeve to such an extent as to prevent the disc 22 being drawn upwardly through the sleeve. When the lifting rod 19 is within the sleeve as shown in the drawing, the lug 21 at the lower end of said rod is disposed at the under side of the thickened or raised portion of the base 10 in position out of alignment with the opening 15. This is best shown by the dotted lines in Fig. 4. Therefore, on the rod being raised the base will be raised 40 with it as will any load on the base.

45 After the stand is loaded, having been assembled as above described, a hood 25 is disposed about the stand or on the stand in a manner to enclose bundles of wire 28. This hood as shown 50 is of relatively thin walled heat resisting steel and has no part in supporting the load of wire bundles being heat treated. When the hood is in place the lower edge of its side walls is within the groove 16 of the base and sand or the like 55 36 may be placed in the groove so as to form a

5 seal with the lower end of the hood. The hood has an upper end wall 26 provided with a central opening and the portion of the hood about said opening is bent or flared downwardly as shown at 27 and rests on the upper end of the sleeve 18 partially entering the sleeve and therewith forming a reasonable seal to exclude gases from the bundles of wire 28. At opposite sides the hood is provided with lifting lugs 29 by means of 10 which the hood may be lifted onto and off the base.

15 In the use of the present apparatus when bundles of wire are to be heat treated the sleeve 18 is positioned over the collar 14 with the lifting rod 19 positioned as shown. The bundles of wire 28 are then dropped into place on the base over the sleeve 18, the latter serving as a centering means. When the complete load is in place the hood 25 is dropped into position completely enclosing the load in a manner to prevent the circulation of gas through it. Lifting rod 19 being disposed with its lug 21 out of registry with the opening 15 in the base, the hook of a crane may be passed through the eye of 20 such rod and the entire apparatus lifted into a furnace.

30 After the required heating the crane may again be connected with the eye 20 and the entire apparatus lifted out of the furnace and deposited on the floor. After the required cooling a hand bar is passed through the eye 20 and the rod 19 is turned to bring its lug 21 into registry with the opening 15 in the base. This is preferably done after the hood 25 has been lifted off and then, by a crane or other means engaging in the eye 20 of the rod 19 the latter is 35 lifted up out of the base and through the pile of bundles on the base. As the rod is picked up the top centering disc 22 thereof will engage the lugs 24 on the inner surface of the sleeve 18 and the sleeve will be lifted up with the rod and carried out of the stack of bundles on the base. Thereafter, there being no center means or sleeve 18 through the bundles of wire they 40 may simply be pushed off the base.

45 In addition to the hood 25 being of heat resisting steel whereby it will not warp or get out of shape it will also be appreciated that this hood is not required to support any of the weight of 50 the bundles on the stand and so does not lose its proper shape and has long life. Rod 19 is also of special heat resisting steel whereby it will not be stretched out of shape particularly during the lifting of the apparatus out of a furnace at which time the rod is hot.

55 When the bundles of wire are piled within a receptacle the latter must be heavy and strong to support the weight imposed on it and resists the transmission of heat to its contents when in 60 the furnace and also has a tendency to elongate and warp. In addition with such a pot it is necessary to handle it with a crane in order to pick it up and dump it at the end of a heat treating operation. Since the sleeve 18 and rod 19 of 65 the present device may be lifted vertically out through the bundles on the base 10 at the end of a heat treating operation it is not necessary to pick the stand up by a crane and dump it. The bundles may simply be pushed off the stand.

70 Having thus set forth the nature of my invention, what I claim is:

75 1. In a combination pot and loading stand, a base having a centrally arranged upstanding collar, an upstanding sleeve at its lower end telescoping with and located by said collar, a lifting rod extending through said sleeve, means detachably connecting said lifting rod with the base, and a centering disc on said rod within the sleeve and above said base.

base, a lifting rod passing through the sleeve and at its lower end detachably interlocking with the base, and a hood of greater diameter than said sleeve and at its lower end resting on the base and at its upper end engaging the sleeve. 5

2. A combination pot and loading stand comprising a base having a centrally arranged non-circular opening therethrough, a vertically disposed sleeve having its lower end on said base, a hood resting on the base and enclosing the 10 sleeve, a lifting rod passing through the sleeve and base, and a lug on the lower end of said rod corresponding to the shape of the opening in the base whereby on passing said lug through the opening and turning the lug the latter is 15 out of registering with the opening in the base and the rod may be used to lift the base.

3. In a combination pot and loading stand, a base, a centering sleeve extending centrally from said base, a lifting rod extending through said 20 sleeve and detachably connected with the base, a hood for enclosing wire bundles on said base, and means whereby on the rod being lifted from the base the sleeve is lifted with the rod.

4. In a loading stand, a base, a centering sleeve 25 independent of and extending vertically from the base, a lifting rod extending through the sleeve, means detachably connecting the rod to the base and adapted to be released by a turning movement relative to the base, and means whereby on 30 the rod being lifted from the base the sleeve is carried with the rod.

5. In a combination pot and loading stand, a base having a centrally arranged upstanding collar, an upstanding sleeve at its lower end telescoping with said collar and resting on said base, a lifting rod passing through the sleeve and at its lower end detachably interlocking with the base, a hood open at its lower end and having an opening through its upper end, and said 40 hood enclosing a load on the stand and resting at its lower end on the base and having the portion of its upper end about said opening flared downwardly and entering the upper end of said sleeve. 45

6. In a combination pot and loading stand, a base, a centering sleeve extending centrally from said base, a lifting rod extending through said sleeve and detachably connected with the base, a hood for enclosing wire bundles on said base, 50 a centering disc on the rod within said sleeve, and lugs on the inner wall of said sleeve above and projecting over said disc whereby on the rod being lifted away from the base said disc will engage said lugs and the sleeve will also be lifted. 55

7. In a loading stand, a base, an upstanding collar on said base, a vertical sleeve at its lower end telescoping with and located by said collar, a lifting rod extending through said sleeve, and means detachably connecting said lifting rod with the base. 60

8. In a loading stand, a base, an upstanding collar on said base, a vertical sleeve at its lower end telescoping with and located by said collar, a lifting rod extending through said sleeve, means detachably connecting said lifting rod with the base, and a centering disc on said rod within the sleeve and above said base. 65

9. In a loading stand, a base, an upstanding collar on said base, a vertical sleeve at its lower end telescoping with and located by said collar, a lifting rod extending through said sleeve, means detachably connecting said lifting rod with the base, and cooperating means on the rod and sleeve 70

75 75

whereby on the rod being lifted away from the base the sleeve is carried with the rod.

10. In a loading stand, a base, an upstanding collar on said base, a vertical sleeve at its lower end telescoping with and located by said collar, a lifting rod extending through said sleeve, and means made effective by relative turning of the rod and base to detachably connect the rod and base.

10 11. In a loading stand, a base, an upstanding collar on said base, a vertical sleeve at its lower end telescoping with and located by said collar, a lifting rod extending through said sleeve, means detachably connecting said lifting rod with the

15 base, a centering disc on said rod within the sleeve and above said base, and means on said sleeve whereby on the rod being lifted away from the base the sleeve is carried with the rod.

20 12. In a loading stand, a base, a centering sleeve detachable with respect to and extending vertically from said base, a lifting rod extending through the sleeve and detachably connected with the base, and means whereby on the rod being lifted away from the base the sleeve is carried with the rod.

25 13. In a loading stand, a base, a centering sleeve detachable with respect to and extending vertically from said base, a lifting rod extending through the sleeve and detachably connected with the base, a means on the rod within the sleeve,

and means on the sleeve to engage with the means on the rod whereby on the rod being lifted away from the base the sleeve is carried with the rod.

14. In an apparatus of the character described, 5 a base, a lifting means extending vertically from the base and adapted to be used to raise and lower the base and a load thereon, a centering sleeve extending upwardly from the base about the rod, a thin walled hood to enclose a charge on 10 the base, and the upper portions of the sleeve and hood cooperating in maintaining the upper portion of the hood concentric with respect to the lifting means.

15. In an apparatus of the character described, 15 a base, a lifting means extending vertically from the base and adapted to be used to raise and lower the base and a charge thereon, a centering sleeve extending upwardly from the base about the rod, a thin walled hood to enclose a 20 charge on the base, and cooperating means between the hood and upper portion of the sleeve and maintaining the upper portion of the hood concentric with respect to the rod.

25 16. In a loading stand, a base, a centering 25 sleeve extending vertically from and independent of said base, a lifting rod passing through the sleeve, and means releasably connecting the rod with the base.

GEORGE S. WATROUS, JR. 30
